Specification for Design.

Patented Feb. 14, 1922.

Application filed December 7, 1921. Serial No. 520,729. Term of patent 14 years.

To all whom it may concern:

Be it known that I, CHARLES F. HUM-
PHREYS, a citizen of the United States, and
a resident of Lancaster, in the county of
Lancaster and State of Pennsylvania, have
invented a new, original, and ornamental
Design for Linoleum, Oilcloth, or Floor
Covering, of which the following is a full,
clear, and exact description, reference being
had to the accompanying drawing, forming
part of this specification.

The figure is a plan view of a piece of
linoleum embodying my design.

I claim:

The ornamental design for linoleum, oil-
cloth, or floor covering as shown.

CHARLES F. HUMPHREYS.
